BUTTER SERVING APPLIANCE

Robert J. Miller, Chicago, Ill.

Application June 4, 1938, Serial No. 211,937

16 Claims. (Cl. 31—20)

My invention relates to butter service appliances, and more particularly to the type suitable for use in homes, and my main object is to provide an appliance of this kind which is sufficiently small and light to be placed on a dining table for the handy serving of butter portions in the form of squares, yet with a sufficient capacity for average family use.

A further object of the invention is to provide an appliance of the above character which carries its own chilling unit and is sufficiently insulated to maintain the butter in proper condition.

A still further object of the invention is to include in the novel appliance a butter receptacle which is of simple design and readily removable for purposes of refilling and cleaning.

Another object of the invention is to construct the appliance with a mechanism which is almost entirely confined to one side of the butter receptacle, so as to have no communication with the same or a tendency to affect or contaminate the butter.

An additional object of the invention is to include in the novel appliance a feed which operates by a single stroke at the front of the appliance and is effective to eject a square of butter each time upon a plate or other support.

Another object of the invention is to combine a frontal element for the butter feed which forms a closure for the appliance while it is not in operation.

A still further object of the invention is to include a connection between the butter receptacle and the chilling unit, whereby to lock the butter receptacle from removal or accidental departure while the chilling unit is in the position of service.

An important object of the invention is to employ parts which are few and simple in the mechanism of the appliance, whereby to enable the latter to be produced at low cost.

With the above objects in view, and any others which may suggest themselves from the description to follow, a better understanding of the invention may be had by reference to the accompanying drawings, in which—

Fig. 1 is a perspective view of the appliance when not in operation;

Fig. 2 is a front elevation, showing the feed in a position to serve a square of butter;

Fig. 3 is a top plan view of the appliance with the cover removed;

Fig. 4 is a longitudinal section of the appliance when not in operation;

Fig. 5 is a view similar to Fig. 4, showing the

positions of the parts when a feeding stroke is taken and also a change in the chilling unit; and

Fig. 6 is a perspective detail of an ejecting element in feed mechanism.

In providing an appliance of the type under consideration, several factors of vital importance must be considered. One is that the butter must be kept and served under sanitary conditions. Another is that sufficient insulation area must be provided to keep the butter properly chilled at least during the period of a meal. Further, the appliance must be small and handy, so as to be moved from place to place without difficulty. Further, the operation must be easy and simple enough for the average person. Finally, the article must be within a price range which the average family can afford. Such devices as have come to my attention for the purpose of dispensing or serving butter in individual units have been deficient in one or the other of the respects outlined, and it has therefore been my intention to combine all possible advantages in the present appliance, whereby the same may prove to be an article of high merit.

In accordance with the foregoing, specific reference to the drawings indicates the casing of the appliance at 10, the same being shaped somewhat like a toaster or similar article and is formed preferably of aluminum to save weight. The casing may be formed with corner fillers 11 or other means to receive screws 12 for a lid 13. On opening the lid, it is noted that the casing has an inner compartment 14 having side walls 15 and 20 and a rear wall 16. Between the side walls and the sides of the casing are lodged slabs 35 or fillers 17 of cork or other heat-insulating material; and the space between the bottom of the compartment 14 and the bottom 18 of the casing is occupied by an insulation filler 19. The lid 13 carries a closed chamber 21 within which is also lodged a filling 22 of the insulating material. Finally, an insulation filling 23 is lodged in the space between the wall 16 and the rear wall 24 of the casing. It is thus evident that the top, sides, rear and bottom of the casing are heat-insulated. 45

In the upper portion of the chamber 14 the wall 15 carries a shelf 25, the latter terminating spacedly from the opposite side wall 20. The shelf 25 is adapted to receive over it a channel-shaped receptacle 26 for a quarter-pound section 50 of butter (not shown), the receptacle being preferably of highly polished or enameled aluminum. The receptacle 26 carries a thickened base 27 which has a tongue 28 toward the wall 15 to freely interlock with a channel 29 carried by the 55

shelf 25, this relation enabling the receptacle to be slid forwardly and rearwardly relative to the shelf. Also, with the casing formed to afford an opening in front—as will be later explained—it 5 is possible to slide the receptacle 26 out of the casing by way of such opening.

The receptacle 26 carries a transverse yoke 30 over its open top, one side of the yoke being short as indicated at 31 and the other side 32 extending 10 down to terminate with a short inward flange 33 under the receptacle. The yoke is thus rendered slidable along the receptacle; and its forward portion is bent down into the receptacle as indicated at 34 to form a backing for the butter section. 15

It is my intention that the yoke 30 form a periodical forward feed or pusher for the butter section in order that the latter may be advanced each time through a distance corresponding to 20 the thickness of the conventional individual butter square, that is, approximately $\frac{1}{4}$ inch. This is accomplished by the partial downward movement of a lever 35 pivoted at 36 to a bracket 45 riveted at 46 to the side wall 20. The free side 25 of the shelf 25 carries a longitudinal channel 37 which is open at the top to slidably seat a ratchet rack 38 whose teeth 39 slope rearwardly. The rack has a slide pin 40 which extends in front of a dwell 41 formed in the underside of the lever 35. This dwell extends with a forwardly rising cam 42, then with a further dwell 43 from which the lever takes a sharp turn 44 in a forward direction. The normal position of the lever 35 is indicated in Fig. 4, the lever being backed against 30 a limiting lug 47 carried by the side wall 20 and so maintained by the pull of a spring 46a between the corner of the lever at the turn 44 and a lug 48 carried by the wall 20. Also, as noted in Fig. 1, the front wall of the casing has an opening 67 formed therein. The lower edge of the opening 67 has a vertical slot 49 at one side. The upper edge of the opening 67 forms a limit for the rise of the lever 35 in response to the pull of the spring 46a.

45 By reference to Fig. 4, it will be evident that the initial depression of the lever acts through the cam 42 to propel the rack 38 a short distance forward, and that the continued depression of the lever accomplishes no further effect upon the rack, owing to the dwell 43. However, the side pin 40 conveniently forms a stop limit for the lever when it has accomplished its full downward stroke, as seen in Fig. 5.

The forward movement of the rack mentioned 50 above is intended to accomplish the feed stroke of the yoke 30, and this is done by the agency of a pawl 50 carried by the yoke. The latter is formed with a return flange 51 from the front on the side facing the wall 20; and the pawl 50 is freely mounted on a pivot pin 52 between the flange and the side 32 of the yoke. The pawl is rearwardly directed to engage one of the ratchet teeth 39 by the upward pressure of a small spring 53 against a heel portion 54 of the pawl. Thus, 55 the pawl 50 forms a connection to push the yoke 30 forward when the rack 38 takes the forward stroke previously explained. This stroke is resisted by a spring 55 between a side pin 56 of the rack 38 and a bracket 57 carried by the rear wall 16. Therefore, when the lever 35 is released and 60 automatically rises to its initial position, the pull of the spring 55 upon the rack also returns the same to its original position but does not affect the position of the yoke 30, since the rack 75 simply trips the pawl against the light resistance

of the spring 53. Thus, it is possible by repeating the previous movement of the rack to accomplish the progressive forward movement of the yoke 30. It will now be apparent that, with the yoke originally set at the rear of the receptacle behind 5 a section of butter, each down stroke of the lever 35 will accomplish the feed anticipated.

It is of course necessary to sever the forward end of the butter section at a point to define the individual butter square, and this action is instituted immediately after the forward feed of the section has been attained, by the further downward movement of the lever 35 from the partially depressed position. Thus, on the down-stroke the lever first causes the forward feed of 10 the butter section, and then accomplishes the severing of the individual butter square; and on the up-stroke the lever permits the return of the rack 38 to its original position.

The severing or cutting of the butter is 20 accomplished by a wire 58 tautly clamped by screws 59 between a pair of brackets 60 bent rearwardly from a cross-plate 61. The latter is vertically slidable behind the front wall of the casing; and it is drawn upwardly by a spring 62 (Fig. 2) 25 which extends from a lug or the like (not shown) carried by the cross-plate to a bracket 64 extended from the side wall 20 of the inner compartment. The cross-plate 61 has a slot 65 at one side to permit the passage of the lever 35 to 30 a position in front of the casing, where the lever receives a suitable finger piece 66. The depression of the latter thus causes the lever to bear down upon the bottom of slot 65 in cross plate 61 after travelling the length of the slot during 35 the advance of yoke 30. Further downward movement of lever 35 slides the plate 61 downwardly with the wire 58 carried thereby to accomplish the severing of the individual butter square by the wire 58. The lower limit of movement of the lever 35 allowed by lever-travel-pin 40 is calculated to permit the wire to be carried down somewhat below the floor of the butter receptacle, so as to assure a full cutting stroke. As 40 the butter section remains stationary during the 45 return of the lever to its original position, nothing will be in the way of the cutting wire 58 during such return.

Provision is made to support and eject the severed butter square from the front of the casing. For this purpose, such front is formed with the aforesaid large opening 67 for which the cross-plate 61 forms a closure when the lever 35 is in the normal or top position. However, when the lever is depressed to induce a butter dispensing action, the frontal opening 67 is gradually uncovered, so that the severed butter square comes into view. It is understood that the front end of the butter section—which later becomes the severed butter square—lies over a shelf 68 60 (Figs. 4 and 6) directed rearwardly from an ejector-plate 69 which is pivoted by means of side ears 70 to a pair of forward brackets 71 carried by the shelf 25, such brackets having stops 72 to prevent the plate 69 from swinging 65 inwardly beyond the vertical position. However, the plate is capable of being swung outwardly to the inclined position indicated in Fig. 5, this being done by the pressure of a finger 73 carried on the inner side of the cross-plate 61 upon a lug 74 directed forwardly from the ejector-plate 70 at a point slightly below its pivot line.

On the down stroke of the lever 35, the ejector-plate is not affected until the moment the cutter wire 58 has fully severed the individual butter 75

square. At such time, the finger 73 bears down on the lug 74, causing the ejector-plate 69 to swing forward and carry with it the severed butter square, this action occurring because the square alone rests on the shelf 25 of the ejector-plate and is therefore carried by the latter. It follows that the down swing of the ejector-plate causes the butter square to be carried to a position of delivery over the plate or other receptacle that may be placed in front of the appliance; also, the highly favorable leverage of the finger 73 relative to the ejector-plate 69 imparts a quick throw to the latter so that any tendency of the butter to stick or lag in its delivery is overcome.

In the construction of the casing front it will be possible to have little or no opening when the appliance is not in operation, so that air from the outside may not enter to impair the efficiency of the cooling unit. In fact, wherever no interference will be had with the movements of parts or the dispensing action heat insulating material will be provided, to more fully insulate the appliance.

When the periodical forward feed of the butter section has caused the last piece to be delivered, the yoke 30 is in the front end of the butter receptacle 26 and forms a bar in case a new section of butter is to be deposited. It is thus necessary to remove the receptacle and yoke, and this is easily done when the casing front is open—as in Figs. 2 and 5—by grasping the yoke and receptacle between the fingers and drawing them forward out of the casing. Nothing in the structure so far described will prevent this action, since the pawl 50 will simply trip over the last few teeth of the rack 38. When the assembly of the yoke and receptacle has been taken out, the yoke may be slid off the receptacle in case either one or the other is to be cleaned or washed, and when the yoke is replaced it is of course slid back to a position over the rear of the receptacle in order to permit the new butter section to be deposited in the latter. With the pawl 50 in the depressed position urged by the spring 53, it is impossible to carry the yoke back into the casing, since the teeth of the rack 38 present an impediment. Therefore, before the assembly of the loaded receptacle and yoke is reinserted into the casing the pawl 50 is manually lifted to trip the hump 51 in the spring 53 and seat the heel 54 of the pawl in a terminal hollow 76 of the spring. The pawl is now sufficiently high to clear the teeth on the reinsertion of the receptacle assembly. However, as the receptacle reaches its rear limit, a lug 77 projected from a bracket 78 carried by the compartment wall 20 bears on the spring 53 in a forward direction to release the heel of the pawl 50 from the depression 76 and permit the pawl to fall of its weight into engagement with the toothed rack profile 39. Obviously, as the first push is exerted by the rack on the pawl, the yoke 30 is moved forward beyond the influence of the lug 77, permitting the spring 53 to resume its influence upon the pawl to keep the latter in engagement with rack.

It is significant that the butter receptacle 26 has a peculiar relation to the shelf 25. Ordinarily it might be assumed that the receptacle could simply seat upon the shelf between suitable side guards to prevent its lateral deviation. However, the fact that the yoke must have a sufficient bearing to prevent binding or uneven action requires that it extend a considerable distance around the receptacle, as more particularly defined by the side 32 and bottom flange 33 of the

yoke. For this reason, the receptacle is formed with the base 27 so as to raise the yoke and accommodate the flange 28 referred to. On the opposite side the elevation of the receptacle permits the interlocking slide joint 28—29. The latter is necessary in order to counteract the tendency of the rack 38 to lift the receptacle on the corresponding side through the pushing influence upon the pawl 50. Consequently, the slide joint of the receptacle with the shelf 25 also acts as a retainer to keep the receptacle level.

The lower portion of the compartment 14 forms a chilling chamber and accommodates a vessel 79 containing cracked ice. The vessel is slideable in and out as indicated by the full and dotted line positions in Fig. 5; and it is preferably indented at the rear as indicated at 80 to accommodate a handle 81 in an internal position, so as to have nothing project from the rear end of the appliance. As it is essential to have a partial if not complete filling of cracked ice in the chilling chamber to maintain the butter in proper condition, I have made the supplying of a new butter section subject to the prior inspection of the ice container 79. Thus, the shelf 25 carries a longitudinal spring blade 82 on its underside, such blade having an upbend 83 and a side lug 83a at its forward end. The front of the ice container 79 is made with an upward extension 84 backed by a block 84a which, when the container is fully inserted, bears upwardly on the blade 82 to position its lug 83a in front of a projection 85 carried by the receptacle 26 opposite the wall 15. Thus, the lug 83a prevents the receptacle from being withdrawn from the casing until the ice container has been withdrawn at least partially from the rear thereof. This releases the blade 82, so that the same drops sufficiently—as indicated in Fig. 5—to clear the projection 85 and permit the receptacle to be removed. Thus, the inspection or refilling of the ice container is a prerequisite to the refilling of the butter receptacle, assuring the maintenance of the new butter section in a properly chilled condition.

It will be evident from the above description that I have provided an appliance which is of a light and portable character, to be placed on a dining table or buffet for immediate service during a meal or for a buffet lunch. The appliance makes it possible to serve the butter in individual amounts usually recognized as sufficient for the average meal or lunch, so that one person does not take more butter than the other and then leaves it unconsumed or wasted. In the present instance, where the person requires or is accustomed to a larger portion of butter, it is a simple matter to dispense or serve an extra square of it. Thus, the butter is not only economically served but is cleanly served without being handled or touched by any person. At the same time it is not open to the air but is maintained constantly in a chilling atmosphere, preserving its quality. The standard quarter-section of butter furnishes quite a few individual squares. Thus, one section is usually sufficient for a day's meals in the average family, making a refilling daily sufficient. From a mechanical standpoint, the appliance utilizes a simple feed which is away from the zone of butter passage, so that a lubricant or moisture carried by the moving parts will not pass into such zone to contaminate the butter. The cutting or severing action is secured by the direct downward stroke of the lever 35, such stroke being favorably di-

rected for manual pressure with a minimum amount of exertion. No other controls are involved in the operation, so that the butter is quickly served and with no particular attention to any part of the appliance other than the lever 35. The butter ejecting device is entirely automatic in action and is accompanied by the closing of the casing front immediately after a butter square has been served, in order to keep 10 the appliance closed as much of the time as possible. The parts entering into the mechanism are of a simple character, permitting the appliance to be manufactured economically and to operate indefinitely without attention or repair. 15 Finally, the appliance is of a nature to be made along sanitary, practical and attractive lines, whereby to form a useful and ornamental article in the home.

While I have described the invention along 20 specific lines, various minor changes or refinements may be made therein from time to time without departing from its principle, and I consider all such changes and refinements as coming within the scope and spirit of the appended 25 claims.

I claim:

1. In a butter serving appliance, a casing having an open front, a butter receptacle within the casing, a periodical forward feed for the butter, 30 a horizontally-pivoted lever to actuate the feed in a partial downstroke and extending forward through the casing front to present a handle, a cross-plate forming a closure for the casing front and in the downward path of the lever, and a severing element for the foremost portion of the butter carried by the cross-plate, the descent of the latter procuring the severing action and uncovering the casing front for the discharge of the severed butter portion.

2. In a butter serving appliance, a butter receptacle, means to place the butter therein with its foremost portion projecting from the receptacle, a shelf for said portion, means to sever the latter from the remainder of the butter, a carrier 45 for the shelf, and means actuated by the severing operation to throw the carrier forward into a position to discharge said butter portion.

3. In a butter serving appliance, a casing having an open front, a cross-plate forming a closure 50 for the latter, a control to open the cross-plate, a butter receptacle within the casing, means to place the butter with its foremost portion projecting from the receptacle, a shelf for said portion, a carrier for the shelf, a cutter carried by 55 the cross-plate and effective to sever said portion from the remainder of the butter when said cross-plate control is actuated, and means actuated by the severing operation to throw the carrier forward into a position to discharge said butter portion by way of the opening created by the cross-plate in the casing front.

4. The structure of claim 3, said carrier being pivoted and said carrier throwing means comprising a lug on the cross-plate, and a projection 65 on the carrier in the path of said lug when the cross-plate undergoes its opening movement.

5. The structure of claim 3, said carrier including an upright section serving as an abutment for said butter portion when the carrier is thrown 70 forward.

6. The structure of claim 2, said carrier being normally upright and assuming a forwardly-inclined position when thrown.

7. In a butter serving appliance, a casing having an outlet, a butter receptacle within the lat-

ter and removable through said outlet, a chilling vessel in the casing, a lock to prevent the removal of the butter receptacle, and a control operated by the withdrawal of the chilling vessel to release said lock.

8. In a butter serving appliance including a butter receptacle, a pusher slidable thereon to advance the butter out of the same, a pivoted pawl on said pusher, a reciprocable ratchet rack, and a spring on said pusher normally engaging said pawl to maintain the same in a position to engage said rack, whereby reciprocation of the latter imparts step-by-step movement to said pusher; said pawl being movable to a position to clear said rack, and said spring including means for holding said pawl in said last named position.

9. The structure of claim 8, a casing for said receptacle, pusher and rack, and means on said casing for automatically releasing said pawl from 20 said spring to permit the return of the same to said rack engaging position when said pusher is moved to its starting position at the rear of said receptacle.

10. The structure of claim 8, a casing for said receptacle, pusher and rack, and a lug carried by 25 said casing, said lug being engageable with said spring to compress the same and permit the return of said pawl to said rack engaging position when said pusher is moved to its starting position 30 at the rear of said receptacle.

11. In a butter serving appliance, a casing having a front opening, a butter support within said casing in alignment with said opening, means for imparting a step-by-step feed to the butter towards said opening, actuating means for said feed means, a cross-plate forming a closure for 35 said opening, and a severing element carried by said plate and adapted to sever a chip from the front end of the butter, said plate being engageable by said actuating means after the completion of a step of the feed to move said plate to uncover said opening and simultaneously sever a chip from said butter.

12. In a butter serving appliance, a casing having a front opening, a shelf in said casing in alignment with the lower edge of said opening, a butter receptacle carried by said shelf, means connecting said shelf and receptacle together and adapted to permit sliding movement of said receptacle towards and away from said opening, means locking said receptacle against said sliding movement, and means for advancing butter relative to said receptacle towards said opening, said last means including a butter engaging portion and a portion at least partially surrounding said receptacle to slidably connect said butter advancing means thereto.

13. The structure of claim 12, a chilling vessel in said casing, and a control for said locking means operative to release said receptacle to permit sliding movement thereof upon at least a partial withdrawal of said chilling vessel from said casing.

14. The structure of claim 7, said lock including a spring arm normally biased to receptacle locking position by said control.

15. In a butter serving appliance including a casing having a front opening, a shelf in said casing in alignment with the lower edge of said opening, and a butter receptacle slidably carried by said shelf; a pusher slidably connected to said receptacle, a pawl carried by said pusher laterally of said receptacle, a reciprocal rack alongside said receptacle and operatively con- 75

5 nected to said pawl for imparting step-by-step movement to said pusher, and overlapping means providing a connection between said receptacle and said shelf adapted to prevent lateral twisting of said receptacle as a result of the thrust of said rack.

10 16. In a butter serving appliance including a casing having a front opening, a shelf in said casing in alignment with the lower edge of said opening, and a butter receptacle slidably carried by said shelf; a pusher slidably connected to said

receptacle, a pawl carried by said pusher laterally of said receptacle, a reciprocal rack alongside said receptacle and operatively connected to said pawl for imparting step-by-step movement to said pusher, and a connection between said receptacle and said shelf for preventing lateral twisting of said receptacle as a result of the thrust of said rack, said connection comprising interengaging L-shaped flanges carried by said shelf and receptacle. 5

10 ROBERT J. MILLER.
